ATTORNEY

UNITED STATES PATENT OFFICE.

PHILIPP KNORPP, OF JERSEY CITY HEIGHTS, NEW JERSEY.

DESIGN FOR AN ARTICLE OF CONFECTIONERY.

SPECIFICATION forming part of Design No. 12,061, dated December 14, 1880.

Application filed November 6, 1880. Term of patent 3½ years.

To all whom it may concern:

Be it known that I, PHILIPP KNORPP, of Jersey City Heights, in the county of Hudson and State of New Jersey, have invented a new and original Design for Articles of Confectionery, of which the following is a full, clear, and exact description, reference being had to the accompanying drawing, making part of this specification, and which represents a perspective view of my improved article of confectionery.

The article is designed for the adornment of Christmas trees; and it consists of a fan-shaped main part provided with a bird at the junction of the web and handle.

A in the drawing represents the fan-shaped main part of the article of confectionery, and B a bird, which is applied at the point of junction between web and handle of the fan. The bird B is without tail, the web of the fan serv-

ing as the tail of the same, and imparting thereby a neat and striking appearance to the article.

Having thus described my invention, I claim as new and desire to secure by Letters Patent—

The design for an article of confectionery, consisting of a fan-shaped main part, A, and a bird, B, arranged at the junction of the web and handle, so that the web forms also the tail of the bird, substantially as shown and described.

In testimony that I claim the foregoing as my invention I have signed it this 29th day of October, 1880.

PHILIPP KNORPP.
